Milwaukee, Wis. 53217

Continuation-in-part of design application Ser. No.
5,049, Dec. 15, 1966. This application Nov. 9, 1967,
Ser. No. 9,341

Term of patent 14 years

(Cl. D13—1)

Fig. 1

Fig. 2

FIG. 1 is a perspective view of the building complex, showing my new design; and

FIG. 2 is a top plan view of the building complex illustrated in FIG. 1.

The opposite side of the building complex not shown is the same in appearance as the side shown in FIG. 1.

The characteristic feature of my design resides in the provision of a central building forming a hub around which a plurality of tower-like buildings are arranged in satellite form.

This is a continuation-in-part of design application Ser. No. D. 5,049, filed Dec. 15, 1966 and now abandoned.

I claim:

The ornamental design for a building complex, substantially as shown and described.
